COMBINATION LOCK

William A. Peters, Chicago, Ill.

Application April 10, 1940, Serial No. 328,809

20 Claims. (Cl. 70—58)

The present invention has for its general object the provision of a very simple, inexpensive, compact, and efficient combination lock adapted particularly to be used for locking books, handbags, and the like, and "zipper" closures for the same, and which may be made in larger sizes for all purposes for which combination locks are used.

A particular object of the invention is to provide a combination lock embodying a series of rotatable disks which is so constructed that none of the operative disks contacts with another or others thereof, and wherein, furthermore, the proper positioning of the several operative disks relatively to each other to effect unlocking, cannot be determined by sense of touch, as is true of many of the more conventional locks of this character.

Another important object of the invention is to so construct the lock as to include therein a reciprocal latch bolt movable manually along a diametric line of the housing.

Another object of the invention is to provide a structure of the type specified wherein the operative disks cannot be moved while the latch bolt is disposed in unlatching position.

Other objects of the invention will be pointed out in or readily understood from the following specification.

A suitable embodiment of the invention is illustrated in the accompanying drawings, wherein:

Fig. 1 is a perspective view of a book equipped with a lock constructed in accordance with the invention.

Fig. 2 is a fragmentary plan view on an enlarged scale showing the lock and the latch member of same, with the latter in released position.

Fig. 3 is a plan sectional view of the lock taken on the line 3—3 of Fig. 13.

Fig. 4 is a fragmentary side elevation of the structure seen substantially from the line 4—4 of Fig. 2.

Figs. 5 and 7 are plan views, respectively, of the fixed ring members of the structure.

Figs. 6, 8 and 9 are plan views showing the rings of the structure which are operative from the exterior of the casing.

Fig. 10 is a plan sectional view taken on the line 10—10 of Fig. 13.

Figs. 11, 12 and 13 are fragmentary detail sectional radial views taken respectively on the lines 11—11, 12—12 and 13—13 of Fig. 2.

Fig. 14 is a fragmentary perspective view

showing the mouth portion of a hand bag equipped with a lock constructed in accordance with the invention and illustrating a modification in construction.

Fig. 15 is a plan view, on a reduced scale, of an operating ring of the lock, which may be substituted for two of the rings illustrated in Figs. 3 and 11—13, inclusive.

The lock as illustrated comprises a substantially cylindrical and shallow sheet metal casing 1, equipped with an extension portion 2 at one point into which the latch bolt 3 may be projected.

The peripheral wall of the casing 1 is equipped with integral projections 4 which are initially straight and are adapted to pass through a cover of a book or wall of a hand bag but which, before being so passed, are bent to the form shown in dotted lines at 5 in Fig. 13 to provide offsets 20 therein which underlie and engage the bottom closure plate 6 of the casing 1 to hold the latter in place, said projections 4 being bent or crimped toward the center of the casing to secure the latter in place.

The latch bolt 3 constitutes one arm of a substantially Z-shaped sheet metal member which the depth of the casing 1 while the main arm 8. The arm 3 rests upon the closure plate 6 which includes the extension portion that constitutes the bottom wall of the extension portion 2 of the casing, said portion 2 being peripherally flanged to constitute a box-like structure. The middle portion 7 of the latch bolt extends throughout the depth of the casing 1 while the main arm 8 35 of said member lies in contact with the upper wall of the casing 1. Said upper wall includes a central offset portion 9 which is provided with a slot through which the shank of an operating button 10 extends, said shank being rigid with said main arm 8 of said latch bolt. The latter as a whole is referred to hereinafter as the member 8.

The upper wall of the extension 2 of the casing 1 is offset downwardly from the offset portion 9 of the upper wall of the main portion of the casing 1 and the same and the portion of the bottom wall 6, which closes said extension 2, are provided with slots 11 to receive the tongue 12 of the latch member 13 which is suitably secured to a member 14 which may be a strap or the slide of a "zipper" closure. Said tongue 12 is provided with a slot 12a to receive the arm of the plunger 8, as shown in Fig. 13.

As shown in Fig. 14, the tongue 15 of a frame member 16 of a hand bag, or the like, may pass

through the extension portion 2 of the casing from the bottom instead of the top.

The offset portion 9 of the casing 1 is bordered by a marginal shoulder 17 which bears three sets of indicia, each set of the same occupying substantially one-third of the arcuate length of said shoulder. The indicia of the several sets may comprise letters of the alphabet or numerals or other characters or devices, but in the instance illustrated, it has been elected to use a set of equally spaced apart numerals for the set A of indicia which is diametrically opposed to the portion 2 of the casing, and to use letters of the alphabet for the indicia of the sets B and C of indicia disposed on respectively opposite side portions of the shoulder 17.

Associated with the respective sets of indicia A, B and C are the operating levers a, b and c, respectively, by means of which the respective rings 18, 19 and 20 within the casing are actuated, the said rings being shown, respectively, in Figs. 3 and 6 (ring 18) and in Figs. 8 and 9 (rings 19 and 20). Each of said rings of the same outer diameter as the inner diameter of the lower portion of the casing 1.

In assembling the lock, the ring 18 is first dropped into the then inverted casing. This ring is equipped with two inwardly projecting tongues 21 which are diametrically opposed to each other (see Fig. 3) and are offset toward and to project into the offset portion 9 of the top wall of the casing 1 (see Figs. 3 and 12). The projections 21 are provided with threaded openings to receive the shanks of set screws 22 (Fig. 12) the heads of which engage the marginal portion of a ring 23 to clamp the latter against said projections 21 against rotation relatively to the ring 18.

The ring 23 fits snugly within the central opening of the ring 18 and is equipped with an arcuate recess 24 in its other edge (Fig. 3).

Immediately below the ring 18 there is mounted a thin sheet metal ring 25 provided with an arcuate projection 26 along its outer edge (Fig. 5) which is engaged in a recess in the peripheral wall of the casing and thus held against rotation, said projection 26 being disposed below the portion of the shoulder 17 bearing the set A of indicia.

Below the ring 25 lies a ring 27 which is integral with the lever a and is equipped with the radially inwardly extending L-shaped arm 28, the inner end flange or tongue 29 of which engages in the recess 24 of the ring 23 and which transmits motion to said rings 23 and 18 as described hereinafter.

Below the ring 27 there lies a ring 30 which is substantially identical with the ring 25 except as to location of its arcuate projection 31 relatively to the recess 32 thereof which receives the arm 7 of a plunger 8 when the latter is retracted from locking position. The ring 25 is equipped with a recess 33 which registers with the recess 32 when both rings 25 and 30 are mounted in the casing 1.

Below the ring 30 lies the ring 19 equipped with operating arm or lever c and below the ring 19 lies another ring 34 which is identical with the ring 30 shown in Fig. 7 reversed in position so that the arcuate projection is disposed to the left of the recess 32.

The ring 20 equipped with operating lever b is disposed between the ring 34 and the bottom plate 6 of the casing.

The rings 18, 27, 19 and 20 are equipped with peripheral recesses 35, 36, 37, and 38, respectively,

corresponding in shape and size with the recesses of the several rings 25, 30 and 34 and are adapted to be brought into register therewith by operation of levers a, b and c to permit the plunger 8 to be retracted from locking position. The tongue 3 of said plunger 8 is bordered by guide projections 39 struck up from the plate 6 (Figs. 3, 10 and 13).

The arcuate portion of the peripheral wall of the casing is composed in part of arcuate flanges bordering the shoulder 17 and in part of arcuate edge flanges of the plate 6, as is illustrated in part in Fig. 4 and in Fig. 3. The latter shows three flanges 40, 41 and 42 which are of stepped formation and have side edge portions spaced apart to snugly receive the arcuate projections of the rings 25, 30 and 34 between them.

The arcuate flanges of the plate 6 are disposed in staggered relation to those of the casing referred to as 40, 41 and 42, the relative arrangement of the two sets of flanges being such that each of the rings 27, 19 and 20 may be rotated through predetermined arcs.

Thus the ring 27 is rotatable through an arc equal to the arcuate length of the set A of indicia while the rings 19 and 20 are rotatable only through arcs of a length such as will prevent the locking recesses thereof from becoming visible through the slots in which the levers b and c are rotatable. This length of arcuate movement is about equal to the arcuate distance between the points X to Y of Fig. 3, less the width of any one of the recesses such as 35 or 37 and is appreciably less than the arcuate spaces occupied by the sets B and C of indicia.

The relative arrangement of the arcuate flanges of the casing 1 and the plate 6 is such that only the arcuate projection, such as 26, of the several fixed rings will be visible together with arcuate portions of the rings 27, 19 and 20 of a length equal to the length of movement of the levers a, b and c, respectively, from the exterior of the casing.

Fragmentary portions of arcuate flanges 41 and 42 of the casing and a fragmentary part of a similar flange of the plate 6 are shown in Fig. 4, the portion of the plate 6 to the right of prong 4 of said figure being devoid of an arcuate flange.

The length of the recess 24 of the ring 23 which is clamped to the ring 18 (the only one not visible from the exterior of the casing) is appreciably less than the length of arcuate movement of the lever of a ring 27 for reasons hereinafter set forth.

The diameter of the central opening of all rings, except the ring 18, is so much larger than that of the latter, that access to the set screws 22 may be had through the openings 45 in the plate 6, the latter and the ring 18 being also equipped with openings 46 and 47 which are in register when the lock recess of the ring 18 is in register with the lock recesses of the fixed rings, the said openings 46 and 47 being inward of the circumferential walls of the openings in the fixed rings and the rings 27, 19 and 20.

Obviously, the positions of the levers b and c with respect to their spacing from the lock recesses of the disks 19 and 20 determine which of the indicia of the sets B and C, respectively, said levers must register with to bring said lock recesses into register with those of the fixed rings and this can be varied only by interchange of rings 19 and 20, respectively, with other similar rings wherein the spacing of said levers b and c

from the lock recesses of said rings is greater or less than that herein illustrated if it is desired to change the combination.

In the instance illustrated the lock presents actually a four point combination which can be changed only as to one of the indicia of the entire set to be used in operating the lock.

It will be noted that the ring 27 is provided with the peripheral lock recess 36 which is offset slightly from a position diametrically opposite to the projection 29 thereof, which engages in the recess 24 of the ring 23, as shown in Fig. 3, said ring 23 being adjustable relatively to the ring 18, as above described.

It may be assumed that the levers *a*, *b* and *c*, as shown in Fig. 2, are in the position wherein the lock recesses of the disks 27, 19 and 20 are in register with the lock recesses of the several fixed rings and that the lever *a* has been previously manipulated to bring the disk 18 into the position shown in Fig. 3, as by having first moved the lever *a* to the extreme right hand limit of its movement and then back to register with the graduations "3" of the scale A and having then been moved into register with graduation "7," as shown.

If it is desired to change the combination, the several disks 18, 19, 20 and 27 are brought into the last-described positions and the latch plunger 8 then moved to the position shown in Fig. 3. This holds the opening 47 of the ring 18 in register with the opening 46 of the bottom wall of the casing and a pin, such as a rivet, is then inserted through opening 46 and into opening 47.

After this has been done, the latch plunger 8 is projected forward and out of the lock recesses after loosening the screws 22, and then while the said pin or rivet holds the ring 18 against rotation, the lever *a* is manipulated to throw the ring 23 into a different position relatively to the ring 18 than as shown, for example, in Fig. 3, the effect of this being to change the position of the recess 24 relatively to the locking recesses of the disk 18. In effecting this adjustment of the ring 23 the lever *a* is moved in to engagement with either of the two end walls of recess 24 and is then moved farther in the same direction until the position of lever *a* registers with the selected graduations on scale A. The screws 22 are then tightened to maintain ring 23 in this new position relatively to the ring 18 and thereafter the operation is exactly as previously pointed out.

Obviously, the number of rings such as 19 and 20 may be increased or diminished and suitable changes made in the length of the slots through which their operating levers project, or said disks 19 and 20 may be omitted entirely to reduce the combination to a two-point one, or if only one of the disks 19 or 20 is used, the combination becomes a three-point one, it being an advantage of the structure that it may be varied in depth according to the number of movable rings intended to be used, thus adapting the structure to be made very shallow, if desired.

The levers *b* and *c* are equipped, preferably, with differently colored knobs or buttons (such as red and blue) while the outer end portion of the lever *a* is maintained in the same finish (such as nickel plating), as the casing 1; said finish being substantially white. Thus the combination may be explained readily by reference to "red, white and blue" buttons or levers, respectively.

In Fig. 15, there is illustrated a ring 49 which may be substituted for the ring 18 and which is

equipped with an arcuate slot 50 and with a lock recess 51. The projection 29 of the arm 28 of the disk 27 will engage in the arcuate recess 50 to actuate the ring 49 in exactly the same manner as ring 18 is actuated via the ring 23, the latter being omitted, obviously, from the structure.

When the ring 49 is used in place of rings 18 and 23, the combination will not be capable of change, except by replacing the ring 49, as shown, with another ring of the same type wherein the spacing between the lock recess 51 and the arcuate slot 50 is changed.

In ordinary use, as on a woman's hand bag, the several levers *a*, *b* and *c* may be maintained in the respective positions wherein the plunger 8 is freely operative to lock and unlock the bag, or one of said levers may be moved slightly out of that position so that it can be quickly restored thereto to permit opening of the bag.

While in the instance illustrated, the rings 18 and 27 are shown as disposed immediately below the top wall of the casing, it will be obvious that the same may be disposed at any level within the limits permitted by the depth of the casing.

I claim as my invention:

1. A commutation lock including a casing of mainly cylindrical contour composed of a top member and a bottom member equipped respectively with downwardly and upwardly projecting flanges disposed in staggered relation to each other with the ends of the flanges of one member abutting the ends of those of the other to prevent relative rotation of said members, the relative heights of the flanges of the respective members being such as to cause their opposed horizontal edges to define a plurality of horizontal slots in the cylindrical contour portion of the peripheral wall of the casing disposed at respectively different elevations and spaced arcuately from each other, and flat sheet metal members rotatable on the axis of said casing portion and disposed in alignment with the several respective slots and equipped with operating levers projecting through the latter.

2. A commutation lock including a casing of mainly cylindrical contour composed of a top member and a bottom member equipped respectively with downwardly and upwardly projecting flanges disposed in staggered relation to each other with the ends of the flanges of one member abutting the ends of those of the other to prevent relative rotation of said members, the relative heights of the flanges of the respective members being such as to cause their opposed horizontal edges to define a plurality of horizontal slots in the cylindrical contour portion of the peripheral wall of the casing disposed at respectively different elevations and spaced arcuately from each other, and flat circular sheet metal members snugly fitting and journaled by said casing portion for rotation about the axis thereof and disposed respectively in alignment with said respective slots and equipped with operating levers projecting through the latter.

3. A commutation lock including a casing of mainly cylindrical contour composed of a top member and a bottom member equipped respectively with downwardly and upwardly projecting flanges disposed in staggered relation to each other with the ends of the flanges of one member abutting the ends of those of the other to prevent relative rotation of said members, the relative heights of the flanges of the respective

members being such as to cause their opposed horizontal edges to define a plurality of horizontal slots in the cylindrical contour portion of the peripheral wall of the casing disposed at respectively different elevations and spaced arcuately from each other, and flat circular sheet metal members snugly fitting and journaled by said casing portion for rotation about the axis thereof and disposed respectively in alignment with said respective slots and equipped with operating levers projecting through the latter, and a plurality of non-rotatable flat sheet metal spacing members equipped with arcuate projections extending into said slots and disposed in staggered relation to said last-named members.

4. A lock of the type specified including a casing of arcuate peripheral contour throughout an arc greater than 180°, said arcuate portion constituting a bearing for a plurality of rotatable members, rotatable members journaled at different elevations within said bearing and each equipped with an operating lever disposed exteriorly of and projecting through an arcuate slot in the peripheral wall of said arcuate wall of said casing, said slots spaced arcuately from each other, said portion of said casing bearing sets of indicia corresponding with the number of said members and disposed relatively to the several slots to guide the operator in the manipulation of said members, each of the latter equipped with a peripheral recess, a reciprocable latch plunger disposed within the portion of the casing bordered by the said arcuate wall portion and movable radially thereof into and out of engagement with the recesses of said members when said recesses are in register with each other at a point between the ends of said arcuate wall of said casing.

5. A lock of the type specified including a casing of arcuate peripheral contour throughout an arc greater than 180°, said arcuate portion constituting a bearing for a plurality of rotatable members, rotatable members journaled at different elevations within said bearing and each equipped with an operating lever disposed exteriorly of and projecting through an arcuate slot in the peripheral wall of said arcuate wall of said casing, said slots spaced arcuately from each other, said portion of said casing bearing sets of indicia corresponding with the number of said members and disposed relatively to the several slots to guide the operator in the manipulation of said members, each of the latter equipped with a peripheral recess, a reciprocable latch plunger disposed within the portion of the casing bordered by the said arcuate wall portion and movable radially thereof into and out of engagement with the recesses of said members when said recesses are in register with each other at a point between the ends of said arcuate wall of said casing, said casing including a lateral extension portion into which one end portion of said plunger projects.

6. A lock of the type specified including a relatively flat, shallow casing having an arcuate wall portion perpendicular to the top and bottom walls thereof and equipped with a plurality of slots parallel with said bottom wall and disposed at respectively different elevations and spaced arcuately from each other, a series of flat, circular sheet metal members journaled in said arcuate wall portion and corresponding in number and respective elevation with said slots and equipped with levers projecting through said slots, each of said members equipped with a peripheral recess and said recesses being adapted

to be brought into register at a point between the ends of said arcuate wall portion by manipulation of said disks, a reciprocable latch plunger mounted upon the top wall of the casing for

5 movement radially of the said arcuate wall portion and bridging the outer edge portion of the uppermost of said members and having a portion thereof disposed to engage in said recesses of said members when said recesses are disposed 10 in register with each other and including a tongue adapted to engage in a companion latch member when said plunger is disengaged from said recesses, said casing including a lateral extension portion into which said tongue projects.

15 7. In a lock of the type specified, a series of rotatable tumblers consisting of parallel flat, sheet metal rings of substantially uniform inner and outer diameters disposed at respectively different elevations and one ring of smaller inner diameter than the remainder thereof, an operating lever for each of the first-named rings,

20 a member rotatable relatively to the last-named ring and provided with means for engaging an operating projection, devices for clamping said member against rotation with respect to the last-named ring, and a projection on one of the first-named rings for engagement with said means for actuating the last-named ring.

25 8. In a lock of the type specified, a series of rotatable tumblers consisting of parallel, flat sheet metal rings of substantially uniform inner and outer diameters disposed at respectively different elevations and one ring of smaller inner diameter than the remainder thereof, an operating lever for each of the first-named rings, a member rotatable relatively to the last-named ring and provided with means for engaging an operating projection, devices for clamping said member against rotation with respect to the last-named ring, and a projection on one of the first-named rings for engagement with said means for actuating the last-named ring.

30 9. In a lock of the type specified, a series of rotatable tumblers consisting of parallel, flat sheet metal rings of substantially uniform inner and outer diameters disposed at respectively different elevations and one ring of smaller inner diameter than the remainder thereof, an operating lever for each of the first-named rings, a member rotatable relatively to the last-named ring and provided with means for engaging an operating projection, devices for clamping said member against rotation with respect to the last-named ring, and a projection on one of the first-named rings for engagement with said means for actuating the last-named ring, said means including spaced apart stop formations for permitting limited free movement of said projection therebetween.

35 10. In a lock of the type specified, a series of rotatable tumblers consisting of parallel, flat sheet metal rings of substantially uniform inner and outer diameters disposed at respectively different elevations and one ring of smaller inner diameter than the remainder thereof, an operating lever for each of the first-named rings, a member rotatable relatively to the last-named ring and provided with means for engaging an operating projection, devices for clamping said member against rotation with respect to the last-named ring, and a projection on one of the first-named rings for engagement with said means for actuating the last-named ring, the latter equipped with spaced apart stop formations disposed in the path of said projection for permitting limited movement of the latter without actuating said ring.

40 11. In a lock of the type specified, a series of rotatable tumblers consisting of parallel, flat sheet metal rings of substantially uniform inner and outer diameters disposed at respectively different elevations and one ring of smaller inner diameter than the remainder thereof, an operating lever for each of the first-named rings, a member rotatable relatively to the last-named ring and provided with means for engaging an operating projection, devices for clamping said member against rotation with respect to the last-named ring, and a projection on one of the first-named rings for engagement with said means for actuating the last-named ring, said last-named ring being disposed above the first-

named rings and said devices being operable through the bottom wall of the casing.

11. In a lock of the kind specified, a casing having an arcuate outer wall portion constituting a bearing and provided with spaced apart slots disposed at different elevations, a plurality of thin, flat rings journalled in said bearing within said casing and equipped with operating levers projecting through said slots, another ring of smaller inner diameter than said first-named ring and devoid of an operating lever, a series of substantially similar rings alternated with the several aforesaid rings and engaged with said casing wall portion against rotation, and a projection on one of the first-named rings for operating the last-named ring, the latter equipped with spaced apart stop formations disposed in the path of said projection for permitting limited movement of the latter without actuating said ring.

12. In a lock of the type specified, a casing having an arcuate peripheral wall portion constituting a bearing and equipped with a series of arcuately spaced apart slots disposed at different elevations, a series of thin, flat rotatable rings journalled in said bearing and equipped with operating levers projecting through said slots, another ring of smaller inner diameter than the first-named rings disposed above the latter, all of said rings confined against vertical movement between the top and bottom walls of the casing, one of said first-named rings operatively associated with the last-named ring to actuate the same, each of said rings equipped with a peripheral recess and all thereof manipulable to bring said recesses into register at a point between the ends of said arcuate wall portion, said casing including a lateral portion having side walls joining the ends of the arcuate wall portion, a reciprocable latch plunger having its main portion disposed in the middle portion of the top wall of the casing and operable through a slot in the latter, said lever including a middle portion adapted to engage in said recesses of said rings when the same are in register and a tongue adapted to engage in a companion latch member when said plunger is projected out of said recesses, and a companion latch member adapted to project through a slot in a wall of said lateral portion of said casing and provided with a slot to receive said tongue.

13. In a lock of the type specified, a casing including an arcuate peripheral wall portion constituting a bearing, a plurality of thin, flat rings journalled in said bearing, at least one of said rings equipped with an operating lever projecting from said casing and equipped also with an inwardly extending projection for actuating another of said rings, means associated with the last-named ring for engaging said projection at spaced apart points in the rotation of the ring equipped with the same, the latter and the ring actuated thereby being each equipped with a peripheral recess and being manipulable to bring said recesses into register at a point between the ends of the said arcuate wall portion of the casing, and a reciprocable latch plunger mounted within the casing and operable to engage in said recesses when the latter are in register to disengage said plunger from a companion latch member, and a companion latch member including a slotted tongue adapted to be projected through a slot in a wall of said casing for engagement with said plunger when the latter is disengaged from said recesses.

14. In a lock of the type specified, a casing including an arcuate peripheral wall portion constituting a bearing, a plurality of thin, flat rings journalled in said bearing, at least one of said rings equipped with an operating lever projecting from said casing and equipped also with an inwardly extending projection for actuating another of said rings, an adjustable device operatively associated with the last-named ring for engaging said projection at spaced apart points in the rotation of the ring equipped with the same, the latter and the ring actuated thereby being each equipped with a peripheral recess and being manipulable to bring said recesses into register at a point between the ends of the said arcuate wall portion of the casing, and a reciprocable latch plunger mounted within the casing and operable to engage in said recesses when the latter are in register to disengage said plunger from a companion latch member, and a companion latch member including a slotted tongue adapted to be projected through a slot in a wall of said casing for engagement with said plunger when the latter is disengaged from said recesses.
15. In a lock of the type specified, a casing equipped with an arcuate graduated scale, a reciprocable latch plunger, a pair of rotatable members within the casing each provided with a recess and both adapted to be positioned to bring said recesses into register at a point wherein the plunger may be moved to latch-release position, one of said members equipped with an operating lever projecting from and with a projection within the casing engaged in a cut-out portion of the latter member for actuating the latter, said cut-out portion permitting free rotation through a given arc of the member equipped with said projection without actuating the other member, and enabling the latter to be moved to a position determined by the position of the operating lever relatively to the graduated scale wherein said last-named member will be positioned to permit the last-named movement of said plunger when the lever operated member is moved to another position on the scale within the limits of its free movement relatively to the member having the cut-out portion.
16. A lock of the type specified including a casing, a member rotatable within said casing and equipped with an operating device projecting from said casing, a companion rotatable member concentric with said first-named member, one of said members equipped with a recess spaced from its axis and the other thereof equipped with a projection adapted to engage opposite walls of said recess when said last-named member is rotated in respectively opposite directions, said recess being of such length that said projection is capable of an appreciable length of movement without engaging either of the walls of said recess, each of said members equipped with a recess spaced from said first-named recess and said projection and adapted to become disposed in register with each other when said members are disposed in a pre-determined relative position within the casing, a latch plunger within the casing, a latch-member adapted to project into the casing for engagement with said latch plunger when the latter is disengaged from said last-named recesses and disengaged therefrom when said plunger is engaged in said recesses.
17. A lock of the type specified comprising a

flat casing provided with a peripheral slot, a pair of flat disks rotatably mounted in said casing, one of said disks equipped with a lever projecting through said slot, cooperating means on said disks whereby the motion of said lever-equipped disk is transmitted to the other disk when the former is rotated through more than a predetermined arc of movement in either direction, a latching device associated with said disks, the latter and said device equipped with interengageable means adapted to permit said device to attain a position to prevent rotation of said disks when the latter are disposed in predetermined relative positions, and a latch member adapted to be engaged by said device when the latter is disposed in position permitting rotation of said disks and to be released from such engagement when said device is disposed in its first-named position.

18. A lock of the type specified comprising a flat casing provided with a peripheral slot, a pair of flat disks rotatably mounted in said casing, one of said disks equipped with a lever projecting through said slot, cooperating means on said disks whereby the motion of said lever-equipped disk is transmitted to the other disk when the former is rotated through more than a predetermined arc of movement in either direction, a latching device associated with said disks, the latter and said device equipped with interengageable male and female formations adapted for interengagement when said disks are in a predetermined position relatively to each other and said device, and a latch member adapted to be engaged by said device when the latter is disposed in position permitting rotation of said disks and to be released from such engagement when said device is disposed in its first-named position.

19. In a lock of the type specified, a casing equipped with a peripheral slot, a rotatable disk mounted in said casing and equipped with a projection projecting through said slot, a second rotatable disk, cooperating means on said disks for effecting limited rotation of the second disk

responsively to rotation of the first-named disk in either direction through an arc of greater than a predetermined length, adjustable means on one of said disks for effecting variation in the positions of the second disk relatively to the casing and with respect to indicia on the latter responsively to the movement of said first-named disk, a latching device associated with said disks, the latter and said device equipped with interengageable means adapted to permit said device to attain a position to prevent rotation of said disks when the latter are disposed in predetermined relative positions, and a latch member adapted to be engaged by said device when the latter is disposed in position permitting rotation of said disks and to be released from such engagement when said device is disposed in its first-named position.

20. In a lock of the type specified, a casing equipped with a peripheral slot, a rotatable disk mounted in said casing and equipped with a projection projecting through said slot, a second rotatable disk, cooperating means on said disks for effecting limited rotation of the second disk responsively to rotation of the first-named disk in either direction through an arc of greater than a predetermined length, adjustable means on one of said disks for effecting variation in the positions of the second disk relatively to the casing and with respect to indicia on the latter responsively to the movement of said first-named disk, means adapted to permit said device to attain a position to prevent rotation of said disks when the latter are disposed in predetermined relative positions, male and female formations adapted for interengagement when said disks are in a predetermined position relatively to each other and said device, and a latch member adapted to be engaged by said device when the latter is disposed in position permitting rotation of said disks and to be released from such engagement when said device is disposed in its first-named position.

WILLIAM A. PETERS.
